UNITED STATES PATENT OFFICE

130,053

DESIGN FOR A HAT RACK OR SIMILAR ARTICLE

Cardross Worth, New York, N. Y., assignor to Marshall & Meier, New York, N. Y., a copartnership composed of Bertha F. Marshall and Clinton E. Marshall

Application April 16, 1941, Serial No. 100,410

Term of patent 7 years

To all whom it may concern:

Be it known that I, Cardross Worth, a citizen of the United States of America and a resident of New York, in the county of New York and State of New York, have invented a new, original, and ornamental Design for a Hat Rack or Similar Article, of which the following is a specification, reference being had to the accompanying drawing, forming a part thereof.

In the drawing:

I claim:

The ornamental design for a hat rack or similar article, as shown.

CARDROSS WORTH.
